COUCH BED

Jacob C. Feldman, Boston, Mass., assignor to New England Bedding Company, Medford, Mass., a corporation of Massachusetts

Application September 9, 1936, Serial No. 99,941

1 Claim. (Cl. 5—55)

This invention relates to couch beds of the extensible type, and its principal objects are to provide a couch bed having nestable sections and a back-rest, the nestable sections being relatively movable so that they may be conveniently drawn to extended position either to form twin beds or a double bed readily accessible without removing the back-rest or any of the parts; to provide a couch bed of the aforesaid type wherein the nestable sections are provided with releasable locking means designed to prevent accidental release when used as a couch; and to provide a couch bed which is of simple and economical construction, having but few parts, which is efficient in operation and reliable in use, and which can be manufactured and sold at a relatively low cost.

Further objects of the invention will be apparent from a consideration of the following description and accompanying drawing, wherein:

20 Fig. 1 is a front elevation of a couch bed constructed in accordance with the present invention;

Fig. 2 is an enlarged section on the line 2—2 of Fig. 1;

25 Fig. 3 is an enlarged fragmentary section of the locking mechanism at the right hand side of Fig. 2;

Fig. 4 is a fragmentary elevation showing the relationship of certain parts when the outer section is in extended position; and

30 Fig. 5 is a section on the line 5—5 of Fig. 4.

The particular embodiment chosen for the purpose of illustration comprises a main or movable outer section 1 and a stationary inner section designated by the numeral 2 (Fig. 2). The main section 1 comprises a box-like structure having a front wall 4 and side walls 5 and 6, the rear being open so that the main section may be drawn from about the stationary section. The top of the main section may be of usual construction for supporting a pair of mattresses 9 which provide the seat cushion when the structure is used as a couch. The outer face of the front and side walls may be provided with a suitable finish, such as 45 textile fabric, which may be secured to the lower mattress so as to hold it in position and give the appearance of continuity therewith. The ends of the side walls are provided with vertically extending angle irons 10 whose lower ends are provided 50 with casters or rollers 11 which support the main section for movement from nested position to extended position.

The stationary section 2 may be of conventional construction having longitudinally and transversely extending frame members 14 and 15 which

carry the usual spring supporting structure and are connected to legs or uprights 16 spaced inwardly from the transverse members, as shown more clearly in Fig. 5. Pivotedly connected to the front ends of the transverse members 15 are hooks 18 (Figs. 2, 4 and 5) normally arranged above the level of cut-out portions or recesses 19 (Figs. 1 and 4) in the legs 10 of the main section, the hooks 18 being disposed to project into the openings 19 when the main section is pulled to extended position, thereby limiting its outward movement, as shown in Figs. 4 and 5. The hooks 18 may be swung upwardly so as to disengage the legs 10, thereby permitting the movable section to be pulled away from the stationary section to 15 provide twin beds. If desired resilient guards 20 (Fig. 5) may be provided on the inner face of the side walls 5 and 6 to prevent the transverse members 15 from binding against the side walls when the two sections are being moved to or from extended position.

A back rest designated by the numeral 22 is supported by the inner section, the back rest comprising a U-shaped member having legs 23 and 24 spaced apart a distance corresponding to that between the rear legs 16 of the inner section, and at least one intermediate longitudinal member 25 which is positioned above the upper surface of the top mattress 9, as shown in Figs. 1 and 2. The lower ends of the legs 23 and 24 are bolted or otherwise secured to the rear legs 16 of the inner section and the upper part of the back rest which projects above the cushions 9 may, if desired, be provided with a suitable covering 28.

In order to hold the sections in nested position and overcome any danger of them becoming accidentally displaced when used as a couch, I provide a centrally disposed releasable latch mechanism (Fig. 3) which is designed so as to hold interlocking parts carried by the respective section in engagement when the sections are in nested position. The latch mechanism comprises an L-shaped member 30 having a vertically extending wing 31 which is secured in any suitable manner to the central part of the inner surface of the front wall 4, and a horizontally extending wing 32 which projects inwardly at approximately the same horizontal level as the upper surface of the front longitudinal frame member 15. The outer end of the wing 32 is curved upwardly and one side of the lower wing 31 is bent inwardly to provide a bracket 34. A latch member 35 is pivotally secured to the bracket 34 so as to swing about a horizontal axis substantially parallel to the frame member 15, this latch being formed with a recess 55

36 and a cam-like nose 37, the upper edge of which is disposed below the wing 32 a distance less than the depth of the wing 15^a of the frame member 15, as shown in Fig. 3. The wing 15^a provides, in effect, a catch or abutment adapted to interlock with the recessed portion of the latch 35 when the sections are in nested position.

The lower end of the latch 35 extends below the lower edge of the front wall 4 and is formed with 10 an enlarged end portion which constitutes a handle 38 by means of which the latch may be released. A small tension spring 40 (Fig. 3), connected at one end to the latch and at its opposite end to the wing 32, normally holds the latch in 15 catch engaging position and the handle 38 inwardly of the front wall 4, but permits the latch to be swung to a released position wherein the interlocking parts are clear of each other so that the outer section may be moved to extended position.

When the outer section of a couch constructed in accordance with the present invention is moved or pushed from an extended position to nested position, the wing 32 first engages the upper surface of the longitudinal member 15 and thus holds the parts at a predetermined horizontal level so that when the nose 37 strikes the lower edge or wing 15^a, these parts become interlocked, as shown in Fig. 3. When the sections are in 30 nested position with the latch 35 in engagement with the wing or catch 15^a, the back and inner section may be tilted (as indicated by the dot and dash lines of Fig. 3) without danger of releasing the latch, and hence when the couch is 35 occupied there will be no liability of the latch becoming accidentally released, even though the occupants lean against the back rest and subject the section to forces which otherwise would separate them.

40 When it is desired to move the outer section to extended position, it is merely necessary to swing

the handle 38 outwardly, using either the hand or toe, and the same movement which releases the latch is effective to cause initial movement of the outer section toward its extended position. When the outer section has been drawn to fully extended position, the hook 18 operates to limit further outward movement in the manner previously explained, but where it is desired to form twin beds, the hook 18 may be swung upwardly from the recesses 19 in the legs 10, thus permitting the sections to be completely separated.

While I have shown and described one desirable embodiment of my invention it is to be understood that this disclosure is intended for the purpose of illustration and that various changes 15 in shape, proportion and arrangement of parts, as well as the substitution of equivalent elements for those herein shown and described, may be made without departing from the spirit and scope of the invention as set forth in the appended 20 claim.

I claim:

In a couch bed having inner and outer sections capable of relative movement from a nested to an extended position and a back rest carried by one 25 of the sections, releasable locking means for holding said sections in nested position, comprising a longitudinally extending frame member carried by one of said sections and defining an abutment, an inverted substantially L-shaped member carried by the other of said sections and arranged so 30 that its upper wing extends horizontally and engages the upper edge of said abutment when said sections are in nested relation, a latch pivotally mounted on the lower wing of the inverted substantially L-shaped member and arranged so as 35 to engage and lock the lower edge of said abutment when said sections are in nested relation, and resilient means urging said latch toward locking position.

JACOB C. FELDMAN.
